UNITED STATES PATENT OFFICE.

ALBERT V. SAMMIS, OF HUNTINGTON, NEW YORK, ASSIGNOR TO FIRE GUN MANUFACTURING COMPANY, INC., OF HUNTINGTON, NEW YORK, A CORPORATION OF NEW YORK.

LIQUID PROJECTOR.

Application filed July 3, 1917. Serial No. 178,407.

To all whom it may concern:

Be it known that I, ALBERT V. SAMMIS, a citizen of the United States, and resident of Huntington, in the county of Suffolk and 5 State of New York, have invented certain new and useful Improvements in Liquid Projectors, of which the following is a specification.

My present invention relates to devices for 10 forcibly projecting liquids from a suitable container, and has for its object to provide improved means for regularizing the flow of the liquid, for preventing leakage (particularly at the outlet) when the apparatus 15 is not in use, and for insuring the proper working of the device irrespective of the position in which it may be held. According to the nature of the liquid employed, the device may be used as a fire-extinguisher or 20 as a sprayer for various agricultural, industrial, or other purposes.

In the embodiments of my invention illustrated by the accompanying drawings, I have located within the container, a pump 25 for producing the pressure required to expel the liquid.

In said drawings, Fig. 1 is a longitudinal section (with parts in outside view) of a form of my apparatus in which the pump is 30 an air-pump; Fig. 2 is a longitudinal section taken substantially on the line 2—2 of Fig. 1; Fig. 3 is a vertical section showing the central portion of Fig. 2 on an enlarged scale; Fig. 4 is a detail vertical section, 35 taken in a plane at 45° to that of Fig. 3, and shows one of the parts represented in Fig. 3; Fig. 5 is an enlarged sectional view of the parts shown at the bottom of Fig. 1, with the pump piston in a different position; Fig. 40 6 is a detail perspective view of a locking member co-operating with the piston rod; Fig. 7 is a detail view with parts in horizontal section on line 7—7 of Fig. 1; Figs. 45 8 and 9 are longitudinal sections corresponding substantially to Figs. 1 and 2 respectively, and showing a species of my invention in which the pump is a liquid-pump; Fig. 10 is a view corresponding to Fig. 3, but illustrating the construction of Figs. 8 50 and 9; Fig. 11 is a face view of a valve stop employed in this second construction; Fig. 12 is a detail diagrammatic developed view of the locking device which co-operates with

the piston rod in the construction of Figs. 8 and 9; Fig. 13 is a cross section on line 13—13 of Fig. 9; Fig. 14 shows, on a reduced scale, a top view of the device represented in Figs. 8, 9, and 13, the pump handle being omitted from Fig. 14; Fig. 15 is a partial longitudinal section corresponding substantially to Fig. 8, illustrating a third form of my invention; Fig. 16 is a cross section on line 16—16 of Fig. 15; and Fig. 17 is a vertical section showing still another form of my invention.

Referring particularly to the construction shown in Figs. 1 to 7, A indicates the preferably cylindrical body of the container having also a preferably bulged head A' and a preferably recessed bottom A''. At one side 70 I have shown a filling nipple B secured to the wall or body A and extending into the container at right angles to said wall. This nipple is normally closed by a screw plug B'. When the container is to be filled with a liquid (say, carbon tetrachlorid for extinguishing fires), it is laid down so that the axis of the cylindrical wall will be horizontal or approximately so, and the nipple B at the top. The plug B' having been removed, liquid can be poured into the container, but only until the level of the liquid rises to the inner (lower) end of the nipple, after which it will be impossible to pour in additional liquid; filling the container entirely is thus prevented, and in this way I insure the retention of an air space which will be of advantage, both as regards the easier starting of the liquid flow, and through the fact that, upon a rise of temperature, the liquid may expand without exerting any material strain on the container. This arrangement of the filling nipple is 85 preferably employed whenever the pump is an air pump.

According to the forms of my invention shown in the drawings, I locate within the container, at one side thereof (preferably the side diametrically opposite to the nipple B, if the latter is employed), a pump by the 100 operation of which the liquid is to be expelled, and in line with the axis of said pump I have shown the outlet nozzle C which may be screwed or otherwise secured to the bottom A'', preferably in such a 105 manner that the nozzle will not project be-

yond the adjacent edge of the wall A; this will protect the nozzle tip when the apparatus is set upright on a table or other flat surface, as will be obvious from Figs. 1, 2, 5 8, 9 and 15.

Referring again particularly to Figs. 1 to 7, in which the pump is an air pump, I have shown an outlet casing 20 adjacent to the nozzle C, a pump barrel 21 one end of which 10 is fitted into a shouldered chamber 20' at the inner end of the said casing, and a head casing 22 located at the head A' and receiving the other end of the pump barrel 21. The outlet casing 20 is secured by a threaded engagement with the nozzle C, or in other 15 suitable manner. The head casing 22 is secured to the head A', say in the manner indicated in Fig. 2, and is provided at its outer end with a chamber containing a packing ring 23 located between cone-faced metal washers 23' and compressed by a threaded metal gland 24 so as to engage tightly the hollow piston rod 25. The outer end of this 20 rod is threaded for connection with a handle 26. The gland 24 and the washers 23' may be removed readily after unscrewing the handle, as the chamber of the casing 22 in which said gland and washers are contained, is of preferably uniform diameter to 25 its outer end. The gland 24 is preferably provided with an annular outward projection 24' surrounded by a packing ring 24" (say, of cork) adapted to fit into a recess at the inner end of the handle, when the latter is in 30 its innermost position; this is to prevent the possibility of leakage along the outer surface of the piston rod 25, or rather the escape of any liquid which may get past the packing 23 when the device is not in use. 35 The handle 26 is shown provided with an air inlet channel 27 leading to the hollow piston rod 25, the latter, near its outer end, containing an inwardly-opening air-inlet valve 28. When the handle is removed from the 40 piston rod, this valve 28 is readily accessible for inspection and renewal, the small housing 29, which contains the ball valve and the spring to seat said ball, being constructed for a threaded engagement with the removable 45 perforated plug 29' having a valve seat. The chamber of the cylinder or barrel 21 adjacent to the head is adapted to receive air from the outside through a channel 30 located in the head casing 22 and controlled by 50 an inwardly-opening spring-pressed valve 31. This casing 22 is also provided with a channel 32, controlled by an outwardly-opening spring-pressed valve 33, to allow air to 55 pass from the upper chamber of the pump cylinder to the interior or main space of the container.

Within the barrel 21 a piston 34 of any suitable construction is secured to the piston rod 25, the open lower end of said rod projecting below the piston as shown. Thus, 60

normally, the interior of the hollow piston rod 25 communicates with the cylinder chamber below the piston, the chamber 20' of the outlet casing 20 forming an extension and virtually a portion of the lower pump chamber. From the chamber 20', a channel 35, controlled by a spring-pressed outwardly-opening valve 36, leads to the interior or main space of the container. 70

It will be obvious that the pump just described is a double-acting air pump which at each stroke will draw air from the surrounding atmosphere into one end of the pump barrel and at the same time force air from the other end of said barrel into the main space of the container. During the inward stroke, the suction valve 31 and the delivery valve 36 will open, the suction valve 28 and the delivery valve 33 remaining closed, while the reverse action will take place during the 80 outward stroke. 85

The air thus forced into the main chamber of the reservoir exerts pressure on the liquid therein and (the outlet nozzle C being open, as in Fig. 5) causes the liquid to be 90 expelled through the nozzle C in the following manner: On a suitable part of the apparatus, say the pump barrel 21, a valve casing 37 is supported, as by means of a plate 37'. This valve casing contains a central chamber 38, in permanent communication with a chamber 20'' of the outlet casing 20, by means of a lateral channel 39 located in the plate 37', said channel communicating with a pipe 40 which extends lengthwise of the container and leads to a duct 41 in the casing 20, said duct being connected with the aforesaid chamber 20''. This chamber is adjacent to the nozzle C, and communicates with it during the operation of the fire-extinguisher, sprayer, etc. The valve casing 37 also contains two end chambers 42, one at each side of the chamber 38, and at the junction of each end chamber with the central chamber I provide a shoulder or seat for a ball valve 43. The seat for this valve 43 is formed in such a manner (see Fig. 3) that the valve will engage it along a line, and not along a surface; sticking of the valve is thus avoided. 100 Between the two valves 43 I locate a sliding separator 44, separate from and loose relatively to said valves, and of such a length as to insure that at any time, at least one of the end chambers 42 will be open to the central chamber 38. Of course the separator 44 is of such a shape as not to obstruct the passage of liquid from the end chambers 42 to the central chamber 38 and from the latter to the channel 39. Each of the end chambers 42 also contains the following parts: A perforated stop 45 to limit the outward movement of the respective valve 43, said stop being projected from, and preferably made integral with, a member 46 pro- 105 110 115 120 125 130 135

vided with an axial passage and with a spherically rounded seat at the outer end of said passage; two elastic (felt) washers 47 on the outside of said member 46; an outer 5 member or thimble 48 fitted over said washers 47 and over a portion of the inner member 46, and engaging a flange on the last-named member to press the latter against a suitable shoulder of the casing 37, said thimble 10 being formed with a spherically rounded seat at the edge of an inturned flange provided at its outer end; and a perforated universally pivoted ball 49 fitted against the two seats of the members 46 and 48 respectively, and also against the inner surfaces of the washers 47. The members 46, 48 and the other parts just mentioned are held in position in any suitable manner, preferably by crimping the edges at the ends of the 15 casing 37 inwardly, as indicated at 37^b (Fig. 3). With each of the ball members 49 is connected a swinging liquid-conveying member or tube 50, preferably of a rigid character, and the free ends of these members or tubes are provided with inlet orifices 20 for the liquid and adapted to move adjacent to the head A' and the bottom A'' respectively. The ball members 49 with their sockets form universal joints for the swinging liquid-conveying members or tubes 50, and preferably the inner surfaces of the head A' and of the bottom A'' are curved spherically to conform to the paths of the free ends of the tubes 50. These ends may 25 be weighted, as shown at 50', to cause them to respond more quickly to changes in the position of the container. Collars 50" of felt or other suitable material may be used if desired to keep the free ends of the tubes 30 from striking against the wall of the container and against the pump casings. The valve casing 37 is preferably located in the longitudinal axis of the container (see Fig. 2) and about half-way between the head A' 35 and the bottom A'', so that the two tubes 50 may be alike.

It will be obvious that gravity will cause the valves 43 and the separator 44, as well as the liquid-conveying members or tubes 50, 40 always to assume such a position as to connect at least one of the tubes 50 with the central chamber 38 and to interrupt connection between the said chamber 38 and that end chamber 42 which temporarily is higher 45 than the other end chamber 42. Thus in Fig. 2 only the lower end chamber and the lower tube are in communication with the central chamber 38. If the pump is operated, the chamber 20" is open to the outlet 50 nozzle C, and the liquid will enter the free end of one or both of the tubes 50, as the inlet orifice of one or both of them dips into the liquid, which will then flow through such tube or tubes and past the valve or valves 43 not seated at the time, into the

central chamber 38, and thence through the channel 39, pipe 40, duct 41, and chamber 20" to the outlet nozzle C.

The chamber 20" not only serves to receive certain parts hereinafter described, but also, by trapping or holding a body of air, performs the function of a wind-chest to regularize the flow of the liquid from the nozzle.

It is desirable that the nozzle C should be 75 closed securely when the apparatus is not in use, so as to avoid spilling or leakage of the liquid contained therein. For this purpose, I have provided a shut-off member controlling the connection of the chamber 20" with 80 the passage of the nozzle C. In the construction illustrated by Figs. 1, 2, and 3, the shut-off member consists of a disk 51 of felt or other suitable material adapted to engage the inner end of a tubular projection C' extending from the nozzle C into the chamber 20". With this particular arrangement, a certain amount of liquid (up to the level of the free end of said projection) may remain at the bottom of the chamber 20", without any danger of spilling this amount when the shut-off member 51 is lifted off its seat. The shut-off disk 51 is contained in a cylindrical socket 52' projected from one side of a sliding disk 52 guided in the chamber 20". 90 This disk, if desired, may fit like a piston against the wall of the chamber, but this is not necessary, that is to say, an air-tight fit is not required. A spring 53, coiled 95 around the socket 52' and bearing against the nozzle C, tends to force the slide 52 and the shut-off member 51 away from the nozzle. On the other (inner) side of the slide disk 52 is located a central projection or pin 52" which extends into a tube or cap 54 open to 100 the chamber 20" but preferably closed to the chamber 20' and mounted to slide in that portion 20" of the casing 20 which separates the chamber 20' from the chamber 20". Both the disk 52 and the cap or tube 54 105 slide in the same direction, which is also the direction in which the piston rod 25 reciprocates, and the lower end of said rod is adapted to engage the upper end of the tube 54, under certain conditions. A washer 54' may 110 be placed around the lower portion of the tube 54, to prevent communication between the chambers 20' and 20" when the parts are in the position (Fig. 5) which they assume when the apparatus is in use. A spring 55 is coiled around the pin 52" and bears 115 against the tube 54, and preferably this spring is appreciably stronger than the spring 53; the latter therefore lifts the shut-off disk 51 from the nozzle C when said disk is released, while the spring 55 tends to separate the tube 54 from the disk 51, and when the cap or tube 54 is pressed down as set forth below, such motion is transmitted 120 yielding to the disk 51, by the spring 55 130

which then presses the said disk against its seat. Inasmuch as the liquid passing through the chamber 20" tends to lift the disk 51, particularly if the latter is constructed as a piston, the spring 53 is not absolutely necessary to make the device operative, and might be omitted.

Below the piston 34, that is to say, on the side of the piston toward the outlet, the piston rod 25 is provided with a diametral pin 25' projecting transversely at each side. In the chamber 20', at the lower end of the pump barrel 21, is located a ring 56 whose central perforation is large enough to allow the lower end of the piston rod 25 to pass through freely (see Fig. 2). At its inner edge, this ring or locking member (Fig. 6) is provided with a pair of diametrically-opposite notches 56' to allow the ends of the pin 25' to pass therethrough in one position, and with two diametrically-opposite, downwardly-open sockets 56'', located between the said notches and adapted to receive and lock the ends of said pin 25' after the same has been turned through an angle of, say 90° from the position in which it registers with the notches 56'. During the normal operation of the apparatus, the pin 25' will be in such a position (say, as indicated by dotted lines in Fig. 5) as to be stopped by engaging the upper surface of the locking member 56 when the piston is at the end of its inward stroke; thus the inner end of the piston rod will be prevented from striking against the cap or tube 54, and the latter as well as the shut-off member 51 will remain in the position shown in Fig. 5, as long as the pump is being operated. When the operation is discontinued, and it is desired to close the nozzle C, the piston rod 25 is turned (by means of the handle 26) to bring the pin 25' to the position indicated by the full circle in Fig. 5, in registry with the notches 56', and then the piston 34 may be pushed inward farther than during the operation of the pump, the ends of the pin 25' passing through said notches until the pin is below the locking member 56, and the end of the piston rod 25 engages the cap or tube 54 and presses it down. This compresses the spring 55 and causes the disk 52 and the shut-off member 51 to move downward also, whereby this member is brought to the closing position, see Fig. 2. By then giving the handle 26 a quarter-turn in either direction, the ends of the pin 25' are brought into registry with the sockets 56'', and the upward pressure of the spring 55 will force said pin ends into the sockets, thus locking the parts against accidental movement. The use of two sliding members 52, 54, with a spring 55 tending to force them apart, insures a proper seating of the shut-off member 51, irrespective of any wear of said parts.

In order to indicate to the user when the

pin 25' is in registry with the notches 56', I may employ the construction shown in Figs. 1, 2 and 7. The handle 26 is made with a projection 26' adapted to register with one or the other of two notches 79' in a flanged ring 79 secured to the head A', at the time the pin 25' registers with the notches 56'. In this position the pump piston may be given a reciprocating motion, but preferably, after the handle has been pulled out a slight distance, it is given a partial turn so as to bring the projection 26' in line with the solid portion of the flanged ring 79; the flange of this ring will thus be in the path of the projection 26' and prevent the handle from being pushed in fully. Of course, the solid portions of the locking member 56 are at that time in the path of the pin 25' and also have the function of limiting the inward movement of the piston, but these parts are concealed from view whereas the projection 26' forms a visible indicator in conjunction with the notches 79'. The notches 79' therefore constitute marks which when in registry with the indicating projection 26' show that the pin 25' is in registry with the notches 56'.

After the gland 24 has been removed as mentioned above, an outward pull on the handle 26 will withdraw not only the packing 23 and the washers 23', but the piston 34 as well, since the diameter of the chamber containing said gland, packing and washers, is greater than the piston diameter.

In the construction illustrated by Figs. 8 to 14 inclusive, the pump is a double-acting liquid pump, and not an air pump. The parts A, A', A'', C, C', 20, 21, 22, 23, 23', 24, 25, 25', 26, 34, 37, 38, 39, 42, 43, 44, 47, 49, 50, 50', 50'', 51, 52, 52', 52'', 53, 54, 54', and 55, are practically of the same construction as in Figs. 1 to 7, although the piston rod 25 may be solid instead of tubular, and the handle 26 is made without the channel 27. The ball stop 45' in this case is shown as a separate piece (Figs. 10 and 11), the dotted lines in Fig. 11 indicating the cross sectional shape of the end chamber 42. The perforated member 46' has a spherically-curved inner seat for the ball 49, the outer ball seat being in the member 48' located exteriorly of the washers 47. The lateral channel 39 connects with a central chamber 57 in a valve casing 37* on the plate 37', the connection of said chamber 57 with the end chambers 58 being controlled by gravity ball valves 59, the outward movement of which is limited by suitable devices, such as the perforated stop disks 60; these disks may be exactly like the stop disks 45' of Fig. 11, except that the disks 45' may be made (as shown) without the central perforation. One of the end chambers 58 is connected by a pipe 61 with the chamber 20' of the outlet casing 20, and therefore

with the lower end or compartment of the pump barrel 21; the other end chamber 58 is connected by a similar pipe 62 with the other, upper end or compartment of the 5 pump barrel 21. A third pipe, 63, which like the pipes 61 and 62 extends lengthwise of the pump, connects the upper pump compartment with the outlet nozzle C by way of a chamber 64, a passage 65, and the chamber 10 20", this connection being controlled by a valve 66 located in the chamber 64. The valve 66 moves between two seats, and when the lower seat is engaged as in Figs. 8 and 9, the outlet nozzle C is in communication 15 with the upper compartment of the pump barrel, while the communication of the said nozzle with the lower compartment of the pump barrel is interrupted by said valve. When the valve 66 engages the upper seat, 20 the communication of the outlet nozzle C with the upper pump compartment is interrupted, but a connection is established from said nozzle through the chamber 20", the passage 65, the chamber 64, a duct 67, 25 and the chamber 20', with the lower compartment of the pump barrel 21. The stop-plate 56* employed in this construction (Fig. 12) has two upwardly-bent tongues 56^a and a pair of downwardly-bent tongues 56^b, the two tongues of the same pair being at diametrically-opposite points. During the reciprocation of the pump piston, the plate 56* limits the downward or inward movement, as described before. When it is 30 desired to lock the piston and close the nozzle C, the piston is turned until the pin 25' registers with the spaces or openings between the adjacent ends of the tongues 56^a, 56^b, and is then pushed in to bring the ends 35 of the pin below the locking plate, in the same manner as described above. By then giving the handle 26 about a half-turn in the proper direction, the ends of the pin 25' are brought to a stop against the down- 40 wardly-bent ends of the tongues 56^b, thus locking the parts against accidental movement.

It will be understood that in this second form of my invention, I may employ the 50 same locking device for closing the outlet nozzle C as in the form first described, or the locking device of Fig. 12 may be used in the said first form of construction, instead of the one there shown; in principle, the two locking devices are practically the 55 same.

It will further be evident that in this second form of my invention, the liquid-conveying members or tubes 50 will act 60 as intake suction pipes for the pump, and the free end of at least one of these tubes will always dip into the liquid, and if one tube or the other is directed upwardly, the corresponding ball valve 43, will, by dropping on its seat, shut off this upwardly-

directed tube (the free end of which is in the air space of the container) from connection with the pump. The other tube 50, however, (by the action of the other valve 43 aided by the separator 44) will 70 be connected with the pump, through the end chamber 42, central chamber 38, channel 39, and chamber 57. This latter chamber will communicate with that compartment of the pump barrel 21 which at the 75 time is the suction compartment, since suction in either pump compartment will be transmitted to the corresponding end chamber 58 through the pipe 61 or 62 respectively, causing the corresponding valve 59 80 to be moved from its seat so as to allow the liquid to pass to such pump compartment from the chamber 57. The two valves 59 will therefore become seated alternately as the pump piston 34 is reciprocated. As 85 liquid is being ejected from the container, air must be admitted to prevent the formation of a vacuum, and for this purpose, as shown in Fig. 8, a ball valve 68 moving outwardly against a suitable seat in the 90 casing 22, and inwardly against a suitable perforated stop 69, is provided to control a vent 22' in the casing 22. In order that no liquid may leak through said vent, a cap or stopper 70 is arranged to engage 95 and close the outer end of the vent, said stopper being then held against said vent by a movable and preferably elastic finger 71, secured to the head A' and to the 100 casing 22, say by a screw 71', and having a perforation for the passage of the piston rod 25. When the handle 26 is pushed in fully (locked position, Figs. 8 and 9), it forces the free or movable end of the finger 71 inwardly to push the stopper 70 105 against the vent as shown. When however, the handle is pulled out, as in operating the pump, the stopper 70 is moved away from the vent 22' by a coiled spring 73, of sufficient strength to overcome the 110 pressure of the finger 71.

This second form of my invention has substantially the same devices as the first form, for locking the piston and for shutting off the outlet nozzle C when the apparatus is not in use, and for rendering the flow of liquid regular or uniform owing to the fact that the chamber 20" forms a wind-chest. The filling of the container might be effected in the same way as in the form first described, or through an opening in the head A', normally closed by a plug B'' (Fig. 9).

The form of my invention shown in Figs. 15 and 16 differs from the second form (Figs. 8 to 14) only in the following particulars: The valves 59 are pressed towards their seats by springs 60', which of course yield when suction tends to move these ball valves from their seats. The plate 37' car-

ries still another valve casing 37^a, containing a chamber or passage 64', while valves 74, under the influence of springs 75, and opening into said chamber 64', control the connection of this chamber with pipes 63' and 63'', of which the former (like the upper end of the pipe 63 in Fig. 8) is connected with the upper compartment of the pump barrel 21, while the pipe 63'' (corresponding substantially to the lower end of the pipe 63 in Fig. 8) leads to the chamber 20' and the lower compartment of the pump barrel. The chamber or passage 64' is connected by a pipe or tube 76 with a wind-chest or air-chamber 77 connected by a tube 78 with the channel 41' leading to the outlet chamber 20'' of the casing 20. The wind-chest 77 retains a trapped body of air which renders the flow of liquid uniform or regular, as explained above in connection with the chamber 20'' of the constructions shown in Figs. 1 to 14.

In Fig. 15 the member sliding in the chamber 20'' is formed as a piston 52^a, the cylindrical hollow projection 52' of which engages a stationary washer 51' made of felt or other suitable material and placed against the inner surface of the nozzle C, which in this case is shown as made without the tubular projection C'. When the piston member 52^a is in its closing position as in Fig. 15, its lower surface is practically flush with the adjacent orifice of the channel 41'. The spring 53 tending to open the outlet of the nozzle, is omitted in this construction; but when the operation of the pump propels liquid under pressure into the outlet chamber 20'', below the piston disk 52^a, such liquid will force the piston 52^a away from the washer 51', thus opening the outlet of the nozzle C. In this particular construction, the nozzle outlet will be closed automatically, by the action of the spring 55, as soon as the operation of the pump is discontinued. The piston rod 25, in this construction, is therefore not relied upon to seat the slide valve upon the outlet of the nozzle C, but only to lock the said valve in such seated or closing position. The other features of construction and operation of the device shown in Figs. 15 and 16, are the same as described above in connection with Figs. 8 to 14. While it is true that in this construction (Figs. 15 and 16) the spring 55 suffices to close the outlet nozzle as soon as the pump stops ejecting the liquid under pressure, so that the action of the piston rod is not required to close said outlet, still when the piston rod is brought down to the locked position, it puts the spring 55 under increased pressure and thus holds the outlet closed more securely.

In Fig. 17, the slide 52, of a construction similar to that of Figs. 15 and 16, has a

loose connection with the cap 54 by means of pins 80 having a sliding fit in the body of the slide 52 and provided with heads below said body, the upper ends of said pins being secured rigidly to the cap 54, or rather to the washer 54* above the flange of said cap. The upper end of the cap 54 is made with a coupling 54^a, for instance in the nature of a longitudinally-split elastic pin adapted to fit into a corresponding socket at the lower end of the piston rod 25. Thus, when the outlet is closed as in Fig. 17, the coupling pin 54^a is within the socket of the piston rod. After the piston rod 25 has been turned to release the pin 25' from the locking member 56, an upward pull on the piston rod will first take along the cap 54 alone and later also the slide 52 when the heads of the pins 80 engage said slide. The outlet will thus be open positively. As soon as the washer 54* engages the partition 20*, further upward movement of the cap 54 will be impossible and continued pull on the handle 26 will cause the socket at the lower end of the piston rod to become separated from the coupling pin 54^a on the cap 54. It will be obvious that when the piston is pushed in to bring the pin 25' under the locking member 56, the coupling pin 54^a will again snap into the socket of the piston rod, and the outlet will be closed in substantially the same manner as described above.

Various modifications may be made without departing from the nature of my invention as set forth in the appended claims.

I claim as my invention:

1. In a liquid-projector, a pump comprising a cylinder and a piston, in conjunction with a casing having intake connections, gravity valves located in said casing and controlling said connections, another casing integral with the first-named casing and communicating therewith, and suction valves contained in said second casing and controlling its connection with opposite ends of the pump cylinder.

2. In a liquid-projector, a liquid-container provided with an outlet, a chamber adjacent to said outlet, a closing member movable in said chamber and controlling its connection with said outlet, a piston member connected rigidly with said outlet-closing member and movable in said chamber, and a liquid-conveying member having an inlet arranged to dip into the liquid, and connected with said chamber between its outlet connection and the piston member, whereby the pressure of the liquid flowing into said chamber will tend to move said piston member and open the outlet.

3. In a liquid-projector, a liquid-container provided with an outlet, a chamber adjacent to said outlet, an inwardly-opening valve controlling the connection of said

chamber with said outlet, a piston member movable in said chamber and arranged to carry said valve from a closed to an open position, and means for conveying liquid to said chamber at a point between said piston member and the outlet connection of said chamber.

4. In a liquid-projector, a liquid-container provided with an outlet, a pump for causing the liquid to be discharged through said outlet, said pump including a member arranged to reciprocate toward and from said outlet, an outlet-closing member movable in the same direction as the reciprocating pump member, a spring-pressed member interposed between said outlet-closing member and said reciprocating pump member, and a guide with which said spring-pressed member has a sliding engagement.

20 5. In a liquid-projector, a liquid-container provided with an outlet, a pump for causing the liquid to be discharged through said outlet, said pump including a member arranged to reciprocate toward and from said outlet, an outlet-closing slide movable in the same direction as said pump member, another slide, likewise movable in this direction, located between said pump member and the first-named slide, and a spring interposed between said two slides and tending to separate them.

6. In a liquid-projector, a liquid-container provided with an outlet, a chamber adjacent to said outlet, an inwardly-opening valve controlling the connection of said chamber with said outlet, a movable member, in contact with the liquid contained in said chamber, and connected with said valve to carry it from a closed to an open position, and means for conveying liquid to said chamber at a point between said movable member and the outlet connection of said chamber, whereby the pressure of the liquid in said chamber will act on the said movable member to bring the valve to its open position.

7. In a liquid-projector, a liquid-container provided with an outlet, a pump for causing the liquid to be discharged through said outlet, said pump including a reciprocating piston, an operating rod extending from said piston to the outside of the container, a handle secured to the outside portion of said rod, a packing gland through which said piston rod extends, said gland being provided with an outward projection, and a packing collar adapted to fit around said projection and into a recess on the

inner face of the handle when the latter is in its innermost position.

8. In a liquid-projector, a liquid-container provided with an outlet, a pump for causing the liquid to be discharged through said outlet, said pump including a reciprocating piston and a piston rod provided with a transverse projection, said rod with its projection being adapted to turn on its axis, a locking member located within the container and adapted to co-operate with said projection to lock or unlock the piston rod, a handle located exteriorly of the container and connected with said piston rod, and indicating means located exteriorly of the container, for showing whether the piston rod is locked or unlocked.

9. In a liquid-projector, a container, a pump for ejecting liquid from said container, said pump including a reciprocating piston, an operating rod extending from said piston to the outside of the container, a head-casing through which said rod passes to the outside of the container, said casing being formed with a chamber whose diameter is greater than that of the pump piston, packing in said chamber, and a removable gland, of greater diameter than the piston, at the outer end of said chamber, whereby, on the removal of said gland, the piston rod can be pulled out with the packing and with the piston.

10. In a liquid-projector, a pump comprising a cylinder and means for exerting suction and pressure therein, in conjunction with a suction intake casing connected with said pump cylinder and having an intake member connected with such casing movably, and held in said casing by an integral part of the casing.

11. In a syringe the combination of a reservoir; a piston chamber in the reservoir having suction inlets to opposite ends thereof and a discharge outlet to the exterior of the reservoir connected with opposite ends of the piston chamber; a piston; a rod to reciprocate the piston extending from the end of the piston chamber opposite to the discharge outlet; a valve operable during the reciprocation of the piston to shut off the discharge outlet from opposite ends of the piston chamber, and valve mechanism operable when the piston is in its innermost position to shut off the discharge outlet from said chamber substantially as and for the purpose specified.

ALBERT V. SAMMIS.
